UNITED STATES PATENT OFFICE.

ROBINSON BURT, OF BUFFALO, NEW YORK, ASSIGNOR TO F. N. BURT COMPANY, LIMITED, OF BUFFALO, NEW YORK, A CORPORATION OF ONTARIO, CANADA.

LABELING-MACHINE.

1,221,831.

Specification of Letters Patent. Patented Apr. 10, 1917.

Original application filed July 10, 1913, Serial No. 778,255. Divided and this application filed March 7, 1916. Serial No. 82,526.

To all whom it may concern:

Be it known that I, ROBINSON BURT, a citizen of the United States, residing at Buffalo, in the county of Erie and State of New York, have invented certain new and useful Improvements in Labeling-Machines, of which the following is a full, clear, and exact description, such as will enable others skilled in the art to which it appertains to make and use the same.

This invention relates to label carrying and feeding devices, and with respect to its more specific features to the construction of a label magazine from which labels are to be taken one by one.

One of the objects of the invention is the provision of a simple construction admitting a backward positioning of the labels relative to a device to which they are to be supplied.

Another object of the invention is the provision of a practical construction for the support of labels of different sizes.

Another object of the invention is the provision of a construction for the purpose referred to which shall be strong and not apt to get out of order.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings forming part of this specification and wherein similar reference characters refer to similar parts throughout the several views,—

Figure 1 is a side elevation of a portion of a labeling machine embodying the invention;

Fig. 2 is a front view, partly in section, of a portion of the mechanism illustrated in Fig. 1; and

Fig. 3 is a plan, partly in section, of the construction shown in Fig. 2, the rotary carrier being eliminated.

The invention is mainly concerned with the provision of a magazine in which a pack of labels may be held so as to coöperate

with a device designed to remove labels one by one from the magazine for further manipulation. The embodiment herein disclosed is a division of applicant's application filed July 10, 1913, Serial No. 778,255, and though illustrated in connection with the rotary label carrier of the prior application, it is to be understood that it is capable of use apart from the other specific embodiments in the prior application. The labels in connection with which the present construction is designed primarily to operate are the usual thin flexible paper sheets or blanks, which may be ornamented and printed upon one face, as for instance more particularly set forth in the prior application, but it is to be understood that the term "label" employed herein comprehends paper blanks of different characters and other sheets capable of being assembled in packs.

Referring now more specifically to the drawings, the numeral 1 represents an upright framework supporting an intermittently rotatable shaft 2, with which rotate label carriages 3 arranged 90 degrees apart and capable of movement radially of the shaft 2, this movement being accomplished through the instrumentality of radially movable blocks 4 connected by links 5 to an oscillatory sleeve 6 on the shaft 2, said sleeve being oscillated through the instrumentality of a connecting rod 7 having a cam roller 8 coöoperating with a groove 9 in a cam disk 10 on a cam shaft 11, all as clearly set forth in the prior application referred to. At the station indicated by the letter *a* the face of the carriage 3 receives a suitable adhesive, such as glue, and when the glued carriage arrives at the station *b*, where it will assume stationary position, rotatively, opposite the pack of labels hereinafter referred to, outward radial movement thereof causes the glued face of the carriage to contact with the bottom label of the pack held in the magazine, said label adhering to the glued face of the carriage and being stripped from the pack upon the inward radial movement of the carriage.

The framework 1 comprises two standards 12, one on either side of the rotary plane of the label carriages and connected

by a frame or cross piece 13 having an opening 14 therethrough immediately opposite station b. The numeral 15 represents a carrier which is movably mounted upon the frame 13 so as to be adjustable thereon. In the preferred embodiment this movable carrier comprises a collar, the opening 16' of which is disposed opposite or immediately above the opening 14 in the frame 13. Connected to the carrier or collar 15 are a plurality of label-supporting fingers 16 spaced apart for the support of labels therebetween, these fingers being preferably of resilient material, as thin steel plates, tapering toward their free label-supporting ends, the character of these fingers permitting them to be flexed and thus portions thereof adjusted so as to be spaced at different distances apart to accommodate labels of different sizes as well as to vary the grasp on the pack of labels. Preferably the fingers are provided at their free lower ends with adjustable flanges 17 to take beneath the lowermost label of the pack near its edges. The carrier 15 is adjusted relative to the frame 13 through the instrumentality of a rotary shaft 18 threadedly connected to the frame 13, as by means of a lug 19 in which the threaded portion of the shaft 18 bears, said shaft being swiveled to the carrier 15 through the instrumentality of the bracket 20 and having a hand-wheel 21 facilitating the rotation of this shaft. By rotating the shaft 18 the carrier 15 may be shifted or adjusted in either of opposite directions, thereby simultaneously adjusting the fingers 16 in planes generally parallel to the plane of the labels when supported between these fingers. It will be observed that by this construction the carrier 15 will be held stationary relative to the frame in the several positions to which it may be adjusted. It will be understood that a pack of labels is placed in the magazine with the faces to be glued presented downwardly, the pack being supported by the flanges 17 or by the grip of the fingers 16, or partly by one and partly by the other, the adjustment due to the movement of the carrier 15 being effected while maintaining the distance between the fingers. The carrier 15 and the frame 13 are provided with coöperating devices adapted to guide the movement of the carrier on the frame, and in the present embodiment these devices comprise tongues 22 on the carrier coöperating with grooves 23 in the frame and adapted to give the carrier a rectilinear movement. In order that the movement of the carrier on the frame shall not be too free, the carrier is pressed against the frame 13 by means of some resilient device, as a spring 24 surrounding a pin 25 projecting from the frame 13 through a slot 26 in the carrier, an abutment 27, in the present instance a nut, serving to effect com-

pression of the spring 24 and to vary the pressing effect thereof.

To facilitate the disposition of the fingers relative to each other and of the label-supporting portions thereof relative to the labels of the pack, the following construction is provided: The numeral 28 indicates a rigid adjusting-device bracket, a portion of which lies upon the carrier or collar 15, this bracket having an arm 29 which depends through the openings in the carrier and frame, and adjacent its lower end carries a finger-adjusting device or hand-screw 30 threaded into the arm 29 and abutting the adjacent finger 16. The numeral 31 indicates a rigid finger-supporting bracket having an upstanding arm 32 to which the upper portion of the finger 16 is securely fastened as by means of a rivet or screw 33. The brackets 28 and 31 are connected to the carrier 15 for adjustment in a plane generally parallel to the plane of the labels, and in the present instance the adjustable connection is effected by means of a screw bolt 34 which passes through slots 35 and 36 in the respective brackets and into the carrier 15. By superposing the brackets 28 and 31 as illustrated, the bolt 34 becomes a common fastening device therefor. It will be understood that any or all of the fingers may be connected to the carrier by means of the bracket construction just referred to, and it will be seen that thereby certain of the fingers are independently adjustable in planes generally parallel to the plane of the labels to vary the distance between the fingers. It will also be noted that when the fingers are disposed on adjacent sides of the opening in the carrier, as illustrated, that the adjustment thereof may be effected in directions at angles to each other. The numeral 37 indicates a scale on the frame 13, and a pointer 38 on the carrier coöperates with said scale to indicate the amount of adjustment of the carrier relative to the frame.

The operation of the device will be apparent from the above description. In the present embodiment the labels or strips to be utilized have a general rectangular outline, and a pack of such labels is inserted from above into position between the fingers, the bottom label of the pack being held by the lateral pressure of the fingers 16, assisted, if desired, by the flanges 17. Should the position of the rotary label carriage be inaccurate relative to the pack, the magazine may be bodily moved by manipulation of the hand-wheel 21 so as to place the fingers in a desired position longitudinally of the path of rotation of the carriages 3. Should the position of the labels transversely of the path of the carriages be inaccurate, certain of the brackets 31 may be adjusted to correctly position the pack. By manipulation

of the hand-screws 39, the fingers may be flexed to accommodate labels of different sizes to vary the pressure on the lateral edges of the pack. In the present embodiment but two of the pins 25 are employed, and they extend through slots 39 and 40 in the respective brackets 28 and 31, the lower end of the springs 24 resting upon washers 41, spanning said slots. The construction provided is quite simple and the several adjustments enable a pack of labels to be accurately positioned and efficiently coöperate with the device that may be employed to remove the labels from the support of the fingers.

Thus by the above described construction are accomplished, among others, the objects hereinbefore referred to.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of the invention, which, as a matter of language, might be said to fall therebetween.

Having described my invention, what I claim as new and desire to secure by Letters Patent is:

1. In a device of the character described, in combination, a plurality of fingers spaced apart for the support of labels therebetween, a movable carrier to which said fingers are connected, a frame supporting said carrier, devices on said carrier and frame adapted to coöperate to guide the said movable carrier relative to said frame, and hand-operated means connected to said carrier adapted to adjust the latter relative to said frame and hold it in stationary position relative thereto.

2. In a device of the character described, in combination, a plurality of fingers spaced apart for the support of labels therebetween, a movable carrier to which said fingers are connected, a frame supporting said carrier, devices on said carrier and frame adapted to coöperate to guide the said movable carrier relative to said frame, and resilient means adapted to press said carrier against said frame.

3. In a device of the character described, in combination, a plurality of fingers spaced apart for the support of labels therebetween, a movable carrier to which said fingers are connected, a frame supporting said carrier, devices on said carrier and frame adapted to

coöperate to guide the said movable carrier relative to said frame, hand-operated means connected to said carrier adapted to adjust the latter relative to said frame and hold it in stationary position relative thereto, and resilient means adapted to press said carrier against said frame.

4. In a device of the character described, in combination, a plurality of fingers spaced apart for the support of labels therebetween, a movable carrier to which said fingers are connected, a frame supporting said carrier, devices on said carrier and frame adapted to coöperate to guide the said movable carrier relative to said frame, and a manually operable rotary shaft threadedly connected to said frame and swiveled to said carrier.

5. In a device of the character described, in combination, a plurality of supporting fingers spaced apart for the support of labels therebetween, a movable carrier, and separate supporting brackets for certain of said fingers connected to said carrier and adjustable thereon in planes generally parallel to the plane of the labels.

6. In a device of the character described, in combination, a plurality of resilient fingers spaced apart for the support of labels therebetween, a movable carrier, separate supporting brackets for certain of said fingers connected to said carrier and adjustable thereon in planes generally parallel to the plane of the labels, separate adjusting-device brackets for certain of said fingers connected to said carrier and adjustable thereon in planes generally parallel to the plane of the labels, and manually adjustable devices connected to said last-mentioned brackets adapted to separately flex said fingers.

7. In a device of the character described, in combination, a plurality of resilient fingers spaced apart for the support of labels therebetween, a movable carrier, separate supporting brackets for certain of said fingers connected to said carrier and adjustable thereon in planes generally parallel to the plane of the labels, separate adjusting-device brackets for certain of said fingers connected to said carrier and adjustable thereon in planes generally parallel to the plane of the labels, and manually adjustable devices connected to said last-mentioned brackets adapted to separately flex said fingers, the supporting and the adjusting-device brackets for the same finger having portions superposed and connected to said carrier by a common fastening.

8. In a device of the character described, in combination, a plurality of resilient fingers spaced apart for the support of labels therebetween, a supporting frame, a movable carrier, devices on said carrier and said frame adapted to coöperate to guide said carrier relative to said frame, separate sup-

- porting brackets for said fingers, connected to said carrier and adjustable thereon in planes generally parallel to the plane of the labels, separate adjusting-device brackets for 5 said fingers, connected to said carrier and adjustable thereon in planes generally parallel to the plane of the labels; manually adjustable devices, connected to said last-mentioned brackets, adapted to separately 10 flex said fingers, adjustable abutments carried by said frame, and springs interposed between said abutments and said carrier pressing the latter against said frame.
9. In a device of the character described, 15 in combination, a plurality of resilient fingers spaced apart for the support of labels therebetween, a supporting frame, a movable carrier, devices on said carrier and said frame adapted to coöperate to guide said 20 carrier relative to said frame, separate supporting brackets for said fingers, connected to said carrier and adjustable thereon in planes generally parallel to the plane of the labels, separate adjusting-device brackets for 25 said fingers, connected to said carrier and adjustable thereon in planes generally parallel to the plane of the labels, manually adjustable devices, connected to said last-mentioned brackets, adapted to separately flex 30 said fingers, adjustable abutments carried by said frame, springs interposed between said abutments and said carrier pressing the latter against said frame, and a manually operable rotary shaft threaded to said frame and 35 swiveled to said carrier, adapted on rotation to adjust said carrier relative to said frame in a plane generally parallel to the plane of the labels.
10. In a device of the character described, 40 in combination, a frame having an opening therethrough, a collar adjustably mounted on said frame, a plurality of resilient fingers spaced apart for the support of labels therebetween extending through the openings in 45 the collar and frame, means adapted to secure the collar in adjusted position on said frame, rigid brackets adjustably connected to said collar having arms overhanging the collar opening, said fingers being secured to 50 said arms, respectively, a rigid adjusting-device bracket connected to said collar, and finger-adjusting devices carried by said last-mentioned brackets adapted to engage said fingers at a point spaced from the connection between said fingers and said arms.
11. In a device of the character described, 55 in combination, a frame having an opening therethrough, a collar adjustably mounted on said frame, a plurality of resilient fingers spaced apart for the support of labels therebetween extending through the openings in 60 the collar and frame, means adapted to secure the collar in adjusted position on said frame, rigid brackets adjustably connected to 65 said collar having arms overhanging the collar opening, said fingers being secured to said arms, respectively, a rigid adjusting-device bracket connected to said collar, finger-adjusting devices carried by said last-mentioned brackets adapted to engage said fingers at a point spaced from the connection between said fingers and said arms.
12. In a device of the character described, 70 in combination, a frame having an opening therethrough, a collar adjustably mounted on said frame, a plurality of resilient fingers spaced apart for the support of labels therebetween extending through the openings in the collar and frame, means adapted to secure the collar in adjusted position on said frame, coöoperating guides on the collar and frame, rigid brackets adjustably connected to said collar having arms overhanging the collar opening, said fingers being secured to 75 said arms, respectively, a rigid adjusting-device bracket connected to said collar, finger-adjusting devices carried by said last-mentioned brackets adapted to engage said fingers at a point spaced from the connection between said fingers and said arms, the two brackets for the same finger being superposed and having slots, bracket-securing devices passing through said slots, a pin on said frame passing through said slots, and a spring around said pin to press said collar against said frame.
13. In a device of the character described, 80 in combination, a frame having an opening therethrough, a collar adjustably mounted on said frame, a plurality of resilient fingers spaced apart for the support of labels therebetween extending through the openings in the collar and frame, means adapted to secure the collar in adjusted position on said frame, coöoperating guides on the collar and frame, rigid brackets adjustably connected to 85 said collar having arms overhanging the collar opening, said fingers being secured to said arms, respectively, a rigid adjusting-device bracket connected to said collar, finger-adjusting devices carried by said last-mentioned brackets adapted to engage said fingers at a point spaced from the connection between said fingers and said arms, the two brackets for the same finger being superposed and having slots, bracket-securing devices passing through said slots, a pin on 90 said frame passing through said slots, and a spring around said pin to press said collar against said frame.
14. In a device of the character described, 95 in combination, a frame having an opening therethrough, a collar adjustably mounted on said frame, a plurality of blank supporting fingers supported by said collar and spaced apart to provide a label magazine in line with the opening in said frame, and means adapted to simultaneously adjust said fingers in planes generally parallel to the plane of the labels while maintaining the distance between said fingers.
15. In a device of the character described, 100 in combination, a frame having an opening therethrough, a collar adjustably mounted on said frame, a plurality of blank supporting fingers supported by said collar and spaced apart to provide a label magazine in line with the opening in said frame, and means adapted to simultaneously adjust said fingers in planes generally parallel to the plane of the labels while maintaining the distance between said fingers, certain of said fingers being adjustable relative to said 105 collar to vary the distance therebetween.
16. In a device of the character described, 110 in combination, a frame having an opening therethrough, a collar adjustably mounted on said frame, a plurality of blank supporting fingers supported by said collar and spaced apart to provide a label magazine in line with the opening in said frame, and means adapted to simultaneously adjust said fingers in planes generally parallel to the plane of the labels while maintaining the distance between said fingers, certain of said fingers being adjustable relative to said 115 collar to vary the distance therebetween.
17. In a device of the character described, 120 in combination, a frame having an opening therethrough, a collar adjustably mounted on said frame, a plurality of blank supporting fingers supported by said collar and spaced apart to provide a label magazine in line with the opening in said frame, and means adapted to simultaneously adjust said fingers in planes generally parallel to the plane of the labels while maintaining the distance between said fingers, certain of said fingers being adjustable relative to said 125 collar to vary the distance therebetween.
18. In a device of the character described, 130 in combination, a frame having an opening therethrough, a collar adjustably mounted on said frame, a plurality of blank supporting fingers supported by said collar and spaced apart to provide a label magazine in line with the opening in said frame, and means adapted to simultaneously adjust said fingers in planes generally parallel to the plane of the labels while maintaining the distance between said fingers, certain of said fingers being adjustable relative to said collar to vary the distance therebetween.

ing fingers supported by said collar and spaced apart to provide a label magazine in line with the opening in said frame, and means adapted to simultaneously adjust said 5 fingers in planes generally parallel to the plane of the labels while maintaining the distance between said fingers, certain of said fingers being independently adjustable at angles to each other in planes generally parallel to the planes of the labels. 10

In testimony whereof I affix my signature, in the presence of two witnesses.

ROBINSON BURT.
